UNITED STATES PATENT OFFICE.

LEMUEL F. HOWARD, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed November 27, 1922. Serial No. 603,461.

To all whom it may concern:

Be it known that I, LEMUEL F. HOWARD, citizen of the United States, residing at Edgewood Borough, in the county of 5 Allegheny and State of Pennsylvania, have invented certain new and useful Improvements in Railway-Traffic-Controlling Apparatus, of which the following is a specification.

10 My invention relates to railway traffic controlling apparatus, and particularly to indicators for use in apparatus of that character.

I will describe one form of apparatus embodying my invention, and will then point 15 out the novel features thereof in claims.

In the accompanying drawings, Fig. 1 is 20 a view showing in front elevation, partly sectioned, one form of speed indicator embodying my invention. Fig. 2 is a vertical sectional view on the line II-II of Fig. 1 and also shows diagrammatically the operating mechanism of the device which controls 25 the indicator. Fig. 3 is a diagrammatic view showing one arrangement of circuits adapted for use in connection with the indicator shown in Fig. 1.

Similar reference characters refer to similar parts in each of the three views.

30 Referring first to Figs. 1 and 2, the indicator comprises a box or container having a back 1, a top 3, a bottom 2, and two sides 4 and 5, all of wood or other suitable material. Movable fastened by means of hinges 35 6 to the side 5 is a front plate 11 of sheet steel or other suitable material, which is secured in its closed position, as shown in the drawings, by means of a hasp and staple 7.

40 A rectangular aperture 12 in this front plate 11, permits of observation of the interior of the box. The aperture is covered by a glass 12^A held in place by a frame 13. Supported in the front plate above the aperture are three signal units 32 which I will 45 describe hereinafter. Fastened to the back 1 of the box by screws 37 is a plate 36 of sheet steel or other suitable material, which supports the moving parts of the indicator.

50 Attached to this plate at its four corners by screws 35^C are forwardly projecting spacing members 35. Supported by these spacing members and attached thereto by screws 35^B is an indicator face 7 which is so disposed

as to be parallel with and immediately behind the aperture 12. Journalled in a suitable bearing 38 in this indicator face and a similar bearing 38^B in the back plate 36 is a shaft 16. Between the aperture 12 and the indicator face 7 and attached to the forward end of the shaft 16 by means of a hub 15 is a pointer 14, disposed at 90° with the shaft and indicating, by its position, the angular position of the shaft 16 with respect to the fixed parts of the device. A flat coil spring 65 17 has one end attached to this shaft by means of a machine screw 19 and has its other end fastened to the plate 36 by means of a pin 18. This spring biases the pointer to the right as viewed in Fig. 1, that is, it 70 exerts a torque in clockwise direction on the shaft 16 and pointer 14. Rigidly attached to the shaft 16 and interposed between the spring 17 and the indicator face 7 is a grooved pulley 20. Passing over this pulley and having one end attached thereto is a flexible inextensible cable 21, which passes 75 through a conduit 26 to the control mechanism shown in Fig. 2. This control mechanism in the form shown, is a governor G 80 comprising a pair of weights 24 which are caused to rotate about a shaft by gearing 25 from an axle 48 of the vehicle on which the indicator is mounted. These weights are 85 connected by means of linkwork to a collar 22. Due to the centrifugal force created by their rotation they tend to move the collar to the left against the force exerted by a spring 23. The cable 21 is attached to this collar 22 and hence communicates the motion 90 of the said collar to the rim of the pulley 20.

When the vehicle is at rest, the collar 22 draws the shaft 16 and pointer 17 to their extreme left hand position against the action of spring 17, and these parts then occupy 95 the positions in which they are shown in Fig. 1. Any increase in the speed of the balls 24, resulting from an increase in the speed of the driving wheels, will permit shaft 16 to move in clockwise direction, Fig. 1, in 100 response to the biasing action of the spring 17. Thus for any one speed of the vehicle there is one and only one position of the pointer 14.

Fastened to the plate 7, and spaced therefrom is a metal segment 8, having thereon three movable clips 9^S, 9^R, and 9^A. These clips may be fastened in any desired posi-

tions along the segment 8 by means of screws 10.

A second conduit 27 communicates, by means of a hole through the bottom 2, with the interior of the box. This conduit protects the wires which connect by means of the binding posts 28 with the three signal units mentioned above and which I will now describe.

- 10 Each signal unit 32 comprises a bushing 30, pressed into a suitable hole in the front plate 11 and has a ground glass roundel 31 with a letter thereon appropriate to the indication of the unit, as S for "Slow", R for "Restricted", and A for "Authorized." Each unit also comprises a lamp holder 33, rigidly attached to the bushing 30 and having a socket for an electric lamp 47. This holder 33 is cylindrical in shape and is provided 20 with an opening 34 in its lower side so located that the light from the lamp may fall upon the pointer 14 and the indicator face 7.

These three lamps are controlled, as shown in Fig. 3 by a relay, designated as a whole by the reference character 41 and having two energizing windings 41^B and 41^C and a rotor element 41^D. This relay is also provided with movable contact fingers 42 and 50 operated by the rotor 41^D and capable of assuming three positions. The relay is controlled by traffic conditions in advance by means not essential to my present invention. It is sufficient to say that when conditions in advance are safe the relay is energized in such a direction that the fingers 42 and 50 are swung to the right closing the normal contacts 42-43 and 50-51, when conditions in advance require caution the fingers are swung to the left closing reverse contacts 42-45 and 50-53, and when conditions in advance are dangerous, the fingers assume an intermediate position and back contacts 42-44 and 50-52 are closed. One form of traffic controlling apparatus which operates in this manner is illustrated and described in an application filed in the United States Patent Office by Lloyd V. Lewis on November 21, 1918, Serial No. 263,607 for railway traffic controlling systems; issued Sept. 7, 1920 as Patent No. 1,351,771, and reissued May 1, 1923, No. 15,592.

Each lamp is designated by the reference character 47 with an exponent corresponding to its positions in the indicator. The slow speed lamp 47^S is provided with a circuit which includes a source of energy such as a battery 46 and the back contact 42-44 of relay 41. The restricted speed lamp 47^R is provided with a circuit which includes the battery 46 and the reverse contact 42-45 of relay 41. The authorized speed lamp 47^A is provided with a circuit which includes the battery 46, and the normal contact 42-43 on relay 41. The contact finger 50

in conjunction with the centrifugal governor G controls some form of speed governing device. As shown in Fig. 3 this is accomplished as follows: The movable collar 22 operates a contact 57 which is moved to the left as the speed of the vehicle increases. This contact coacts with three brushes 54, 55 and 56 of different lengths in such manner that at speeds below some low speed such as 15 miles per hour the contacts 57-54, 57-55 and 57-56 are all closed, at speeds above 15 miles per hour and below some intermediate speed as 35 miles per hour only the contacts 57-54 and 57-55 are closed, and at speeds above 35 miles per hour and below some high speed as 65 miles per hour only the contact 57-54 is closed, while at speeds above 65 miles per hour none of these contacts are closed. A magnet M is arranged so that when de-energized the vehicle brakes are applied. This magnet is provided with a circuit including the battery 46, contact 57-54 on centrifuge G, and normal contact 50-51 on relay 41, a second circuit including the battery 46, contact 57-55 on centrifuge G and contact 50-53 on relay 41 and a third circuit including the battery 46, the contact 57-56 in centrifuge G and contact 50-52 on relay 41. Thus it is clear that when traffic conditions in advance are safe the lamp 47^S will be lighted and an automatic brake application will not be made unless the train speed exceeds 65 miles per hour. If traffic conditions in advance require caution, the lamp 47^R will be lighted and brake application will be made if the train speed exceeds 35 miles per hour. If traffic conditions in advance are dangerous the lamp 47^A will be lighted and brake application made if the train speed exceeds 15 miles per hour.

The calibration of the indicator may be made by running the vehicle out on the road, noticing at what positions of the pointer 14 the brake application takes place for the various speed limits corresponding to various traffic conditions, and fastening the movable clips opposite such positions of the pointer. The driver will then have complete information for the operation of his vehicle because he will be informed of the speed limitations under which he is running by noticing which of the lamps is lighted, and he will merely have to watch the approach of the pointer to the clip associated with such lamp in order to determine when the automatic brake application is about to occur.

In the side 5 of the box are two ventilating holes 29, covered with fine mesh metal gauze, to allow free circulation of air but prevent the entrance of insects, dirt, or other extraneous matter.

Although I have herein shown and described only one form of apparatus embody-

ing my invention, it is understood that various changes and modifications may be made therein within the scope of the appended claims without departing from the spirit and scope of my invention.

Having thus described my invention, what I claim is:

1. In combination, a vehicle, a speed-responsive device on said vehicle, a pointer operated by said device, a plurality of adjustable members adjacent to the path of the said pointer, and a plurality of lamps associated with said members and illuminating them and controlled by traffic conditions ahead of the said vehicle.
2. In combination, a vehicle, a speed-responsive device on said vehicle, a pointer

operated by said device, a plurality of adjustable members adjacent to the path of the said pointer, and means controlled by traffic conditions ahead of the vehicle for illuminating said members.

3. In combination, a vehicle, a speed-responsive device on said vehicle, a pointer operated by said device, three adjustable members adjacent to the path of the said pointer for indicating in conjunction therewith, slow, medium and high speed limits, respectively, of the said vehicle, and a plurality of lamps associated with said members and illuminating them and controlled by traffic conditions ahead of the said vehicle.

In testimony whereof I affix my signature.

LEMU^E F. HOWARD.
